We claim:

The ornamental design for a pool or the like, as shown.
